(57) CLAIM

We claim the ornamental design for a bath cushion for an infant, shown and described.

DESCRIPTION

FIG. 1 is a top perspective view of a bath cushion for an infant showing my new design;

FIG. 2 is a top view thereof;

FIG. 3 is a front view thereof;

FIG. 4 is a right side view thereof;

FIG. 5 is a bottom view thereof;

FIG. 6 is a left side view; and,

FIG. 7 is a back view thereof.

The present invention relates generally to a bath cushion, and more specifically, to a bath cushion used in the bathing of an infant.
